UNITED STATES PATENT OFFICE.

CHARLES P. GIFFORD, OF NEW YORK, N. Y.

WHEEL.

1,364,877.

Specification of Letters Patent. Patented Jan. 11, 1921.

Application filed January 14, 1920. Serial No. 351,479.

To all whom it may concern:

Be it known that I, CHARLES P. GIFFORD, a citizen of the United States, residing at New York, in the county of New York and State of New York, have invented certain new and useful Improvements in Wheels, of which the following is a full, clear, and exact description.

The essential prerequisites of wheels of a certain class, for example, such as are adapted for use with automobiles, are reasonable weight and bulk, very great strength to resist all strains, particularly side or lateral thrusts, and great durability. The ingenuity of inventors and designers has been taxed to the utmost to produce, economically, satisfactory wheels of this nature, but as all those skilled in this art well know, the coveted goal has not been fully reached.

In an endeavor to improve upon the plans of construction heretofore followed in the production of such wheels, I have discovered a wheel and a method of making the same which more nearly meets all of the above enumerated and exacting requirements than anything that has come under my observation, and this discovery forms the subject of my present application for Letters Patent.

According to this my invention I build wheels on the same principle that a cabinet-maker builds a veneer. That is to say, the wheel is built up by winding spirally a thin strip of wood or any equivalent material, one convolution being firmly united to another by a suitable adhesive substance until a solid body is obtained of approximately the dimensions of the wheel desired. After this has been compacted and dried, it is sawed up into bodies of suitable thickness, if it be of sufficient thickness, and each piece is then turned down to the exact form and dimensions of the finished wheel. Equipped, if it has not already been built up on such element, with a suitable bushing, and a rim, it is then painted, polished, covered with a metal surface or otherwise finished off as a complete wheel.

Such wheels have all the desirable properties of the best forms of wooden spoked wheels, and possess to a most marked degree great strength, rigidity and power to resist all strains, whether radial or transverse.

In the accompanying drawings I have illustrated this improved wheel.

Figure 1 is a central vertical section of a finished wheel.

Fig. 2 is an illustration of the manner of building it up.

Fig. 3 is a portion on an enlarged scale of a metal-covered wheel.

Only such means as are now well known in the art are required to build up these wheels. I cut or prepare a long strip of wood or fibrous material 1, such as is used in making veneer, and it is generally desirable that when by the nature of the material these strips are limited in length, to splice a number of them in known ways together end to end. This strip is wound spirally preferably upon a bushing or mandrel 2, glue or other adhesive substance being applied to the contacting surfaces, and sufficient pressure employed to unite the convolutions closely and firmly.

When by this means a body of the desired diameter is obtained, it is sawed up into bodies of approximately the thickness of a wheel, unless the strip is only wide enough for one wheel, and then turned down and finished off to give it an attractive form and appearance. If for use in an automobile, it is fitted with a metal rim 3 to receive a pneumatic tire 4. It may be ornamented in any desired manner, or it may receive a coating 5 of metal of any desired kind which may merely serve as an ornament or as a protection against the weather or add very materially to the strength and appearance of the wheel.

The specific method of building up what I designate as the veneer is not of the essence of the invention. For example, after the spiral has reached a certain substantial diameter, a second or other veneer strip 6, as indicated by the dotted lines in Fig. 2, may be introduced and used. The material used is also a matter of selection. Various woods such as are habitually used for making veneers may be employed or other suitable fibrous materials.

I am aware that various bodies including wheels have been formed by winding upon itself a more or less flexible strip of material, and that the rims for bicycle wheels and the like have been formed by concentric and also spirally wound and united strips of wood, but in cases where wood has been used for this purpose it was of substantial thickness and not of the nature of what is known as true veneer. This made it impossible to wind more than the mere rims of wheels of substantial diameter as the material could

not be bent into convolutions of smaller diameter without breaking.

According to my invention I make the entire wheel body of the wound strip or strips 5 of wood, which therefore must be of the nature of a true veneer, in order that it may be wound upon a mandrel of small diameter.

Having now described my invention, what I claim is:

10 1. A wheel for automobiles comprising a body made up entirely of a spirally wound strip of wood veneer united, compacted and finished to the desired conformation.

2. A wheel for automobiles comprising a

body made up entirely of a spirally wound 15 strip of wood veneer united, compacted and finished to the desired conformation and coated with a metal.

3. The method of making the bodies of automobile wheels which consists in wind- 20 ing, uniting and compacting a strip of wood veneer upon itself, then sawing up the wound material in lengths substantially equal to the thickness of the wheel body and turning the latter to form the finished wheel. 25

In testimony whereof I hereunto affix my signature.

CHARLES P. GIFFORD.
